TURN INDICATOR WITH AUTOMATIC CANCELLATION

Cleafe A. Best, Jackson, and Lloyd E. Johnson,
Parma, Mich., assignors to Sparks-Withington
Company, Jackson, Mich., a corporation of Ohio

Application October 14, 1950, Serial No. 190,235

3 Claims. (Cl. 200—61.34)

1

The present invention relates to improvements in signaling apparatus for vehicles of the type wherein the operator is provided with manually initiated means for indicating the direction in which the vehicle is to turn; there being automatic means for cancelling the turn indication upon completion of the turn.

One of the objects of the present invention is to provide an apparatus of the type defined which is especially adapted for installation as an accessory upon vehicles now in use.

Another object is to provide a turn indicating apparatus which is adapted to be installed upon various vehicles of different make and model without alteration or the provision of special adaptors.

A further object of the invention is to provide an improved self-cancelling turn indicator which may be inexpensively manufactured and installed upon the steering column of the automobile.

These and other objects and advantages will become apparent when taken with the following specification and claims and the accompanying drawings, in which:

Fig. I is an elevational view showing the manner in which the present invention is adapted to the steering wheel and column,

Fig. II is a top view of the turn indicator switch mechanism with the upper section of the housing in position,

Fig. III is a view similar to Fig. II with the upper section of the housing removed and taken on the line III—III of Fig. I.

Fig. IV is an end view of the switch mechanism with the end plate removed with the rocker plate in its neutral position,

Fig. V is a view similar to Fig. IV with the rocker plate in a position indicating a left turn,

Fig. VI is a detail of the switch actuator attached to the steering wheel, and

Fig. VII is a detail side view of the switch box with the side shown broken away to expose the interior.

Referring to the illustrated form of the invention, the turn indicator switch mechanism comprises a housing or frame structure 10 having upper and lower sections 12 and 14 separated along the line 16. Section 12 is notched at 18 to receive the lever 20 which is engaged at 22 to rock the same from its "neutral" position into either a "right" or "left" turn indicating position. A screw 24 holds the sections 12 and 14 together and also serves as a pivot by passing through a hole 26 in the lever 20.

As more clearly shown in Fig. III, the lever

is flattened at 28 to provide a flat wide portion in which the pivot hole 26 and the elongated slot 30 are defined. The outer end 32 is preferably of round section to be received in the elongated hole 34 in the rocker plate 36. The switch box 38 has a center post 40 which extends into the slot 30. Spring means 42 within the box 38 urges the contact blocks 44 into their neutral position, as well as the post 40, away from both the "right" and "left" contacts (not shown) which, when engaged by the contact blocks 44, close the associated circuits in which the turn indicator lights (not shown) are located. The post 40 has a yoke 40a which engages the blocks 44 with a slide fit except for the engagement with the shoulders 40b of the blocks 44, the shoulder engaged depending upon the direction of movement of the post 40. Movement of either block 44 compresses the spring 42 with the at rest position being shown in Fig. VII.

When the lever 20 is rocked into either of the dotted line positions shown in Fig. II the plate 36 is rocked around its pivot 48 with the spring ball detent 50 engaging into one of the depressions 52 to hold the plate 36 in its rocked position against the stress of the spring means 42 tending to urge the plate 36 into the "neutral" position of Fig. IV. In the position of Fig. V the lever 20 is being held in the dotted line position 54 of Fig. II and the circuit is closed indicating a "left" turn. In the position 56 a "right" turn would be indicated.

Manual cancellation of the switch mechanism may be effected by engaging the lever 20 in either of the dotted line positions 54 and 56 of Fig. II and moving the same into the full line or "neutral" position. To accomplish cancellation automatically, fingers 58 and 60 are pivoted to the plate 36 on shoulder rivets 62. A spring 64 connected to extensions 66 holds the fingers 58 and 60 against stops 68 formed by deflected position of the plate 36. The arrangement permits the fingers 58 and 60 to rock in a direction away from the stops 68 without rocking the plate 36. However, if a force is applied to the fingers 58 and 60 which acts against a stop 68 the plate 36 will be rocked about its pivot 48.

Slots 70 are provided in the section 12 through which the fingers 58 and 60 project when the plate 36 is rocked out of its "neutral" position as shown in Fig. V. With the "right" turn circuit closed as shown in Fig. V, the finger 58 is projected through the slot 70 to locate the end 72 of the finger 58 beyond the section 12 in a position to be engaged by a part or parts on the

steering wheel. Such engagement, with the steering wheel being rotated clockwise, will rock the finger 58 away from its stop 68 and no movement is imparted to the plate 36. Upon completion of the right turn, counter-clockwise rotation of the steering wheel will result in the end 72 of the finger 58 being engaged. As relative movement thereof counter-clockwise is prevented by the stop 68, the plate 36 will be rocked into the "neutral" position of Fig. IV under the initial action of the spring means 42 after the initial holding action of the detent 50 in the depression 52 has been overcome.

While it is anticipated that the finger ends 72 may engage the spokes of the steering wheel, in practice it has been found desirable to equip a single spoke of the wheel or the hub with a projection extending into the path of which the portion 72 of the fingers 58 and 60 may be projected. Such a projection may take many forms. In Fig. VI is shown a metal stamping 74 having barbs 76 to prevent relative movement on the spoke 78. A spring 80 holds the stamping 74 firmly in position with the extension 82 engaging the ends 72 of the fingers 58 and 60 to rock the plate 36 to effect automatic cancellation of the turn manually indicated after the turn is completed.

It will be noted that the axis of the pivots for the lever 20 and plate 36 are disposed in the same plane although normal to each other. While this is the preferred arrangement, it is anticipated that the angularity between the axis of the pivot just mentioned may be changed from that shown, all within the scope of the invention.

Operated in time relationship with the contacts controlling the turn indicating circuits are contacts in the circuits of the light 84 which is located below the color lens 86 of the top of section 12. When the turn indicator is functioning out of its "neutral" position the lens 86 will glow to indicate the operating condition of the device.

The mounting structure for the switch 10, as shown in Fig. I, comprises a channel member 88 to receive the steering wheel column 90 with a strap type clamp 92 holding the same in adjusted position. At the upper end of the member 88 is a lateral bracket member 94 slotted at 96 to receive the adjustment bolt 98. The lower face of the section 14 is formed with a groove 102 in which the bracket 96 has a sliding fit to prevent pivotal movement about the bolt 98 yet permit the switch 10 to be moved in and out relative to the column 90. The electrical conduits are indicated at 104 with a suitable clamp 106 holding the same along the column 90. Adjustment of the member 88 along the column 90 will adjust the position of the ends 72 of the finger 58 and 60 relative to the operating part on the steering wheel 108.

We claim:

1. A turn indicator switch mechanism adapted to be installed adjacent the steering wheel of an automobile with automatic cancellation performed by the rotation of the steering wheel comprising a rockable member, pivot means about which said member is rocked in opposite directions, a pair of fingers supported on said member for bodily movement therewith and relative movement thereto only as rotational movement about fixed axes; pivot means for said fingers upon said member to provide said fixed axes, stops upon said member, spring means engaging

5 said fingers to rock the same into engagement with said stops, a manually actuated lever for rocking said member having a handle at one end and a portion at the opposite end engaging said member to rock the same to "right" or "left" positions from a "neutral" position, a pivotal mounting for said lever intermediate its ends for rocking movement thereof about an axis substantially normal to the axis about which 10 said member is rocked by said lever, spring detent means for holding said member in "right," "left" and "neutral" positions, a switch adapted to close and open a pair of turn indicating circuits operatively engaged by said lever to one side of its pivot to be actuated thereby upon rocking movement of said lever and member, said fingers upon rocking movement of said member into "right" and "left" positions being projected alternately into the path of means rotatable with the steering wheel whereby engagement with said fingers in a direction abutting said stop results in said member being rocked from its "neutral" position and engagement with said finger in the opposite direction results in said fingers rocking on their respective pivots relative to said member to permit the means moving with the wheel to pass without actuation of said member.

2. A turn indicator switch mechanism for vehicles comprising a housing, a rockable plate having a pivot supported from said housing, a pair of fingers pivotally mounted on said plate in spaced relation to said pivot and on opposite sides of a plane through the axis of said pivot, stops on said plate engaged by said fingers to limit relative pivotal movement of said fingers on said plate in one direction while permitting such movement in an opposite direction, spring means holding said fingers against said stops and yielding to the pivotal movement of said fingers relative to said plate, "right," "left," and "neutral" detent stations on said plate, a positioning detent supported on said housing for engagement with said stations upon rocking movement of said plate, a slot in said plate elongated along an axis in said plane, a switch having "right," "left," and "neutral" positions, spring means energized by movement of said lever into either "right" or "left" positions for continuously urging said switch into "neutral" position, an operating lever supported on said housing for rocking movement about a pivot having its axis disposed in said plane and angularly disposed to the axis of said plate pivot, said lever extending in opposite directions from its pivot to provide an outer handle portion and an inner plate actuating position, said inner portion at its extremity engaging in said elongated slot to rock said plate upon rocking movement of said lever, an operative connection between said switch and a part of said lever between said extremity and said lever pivot to actuate said switch into "right" and "left" positions, structure for supporting said housing in a position projecting alternately said fingers into the path of a part moving with the steering wheel of the vehicles with said plate rocked into "right" or "left" positions with said fingers yielding to movement away from their respective stops and rocking said plate toward the neutral position when urged toward their respective stops, said detent holding said plates in said "right" and "left" station against the action of said second spring means with said second spring means urging said plate into neutral position.

3. A turn indicator switch mechanism of the self cancelling type adapted for installation on

the steering wheel column of a vehicle comprising a casing, a bracket for connecting said casing to said column beneath the wheel, an opening defined in one side of said casing, a hand lever extending through said opening, a pivotal connection with an intermediate portion of said lever located within said casing adjacent said side for supporting said lever for pivotal movement about an axis substantially parallel to the longitudinal axis of said column, a switch within said casing, an actuator means for said switch within said casing including a rocker member, a pivotal connection for said rocker member for supporting the same for rocking movement about an axis substantially normal to said first axis, the inner end of said lever engaging with said member to rock the same, a pair of fingers upon said member, opening in the upper side of said casing

10

through which said fingers extend upon rocking by said actuation by said lever to selectively position one of said fingers into a plane parallel to the steering wheel, means pivotally connecting said fingers upon said member and abutment structure on said member engaged by said finger to limit the pivotal movement of said finger in the opposite direction.
